No. 767,776.

PATENTED AUG. 16, 1904.

G. G. TURNER.

TORPEDO.

APPLICATION FILED JAN. 5, 1904.

NO MODEL.

UNITED STATES PATENT OFFICE.

GEORGE G. TURNER, OF DOVER, DELAWARE, ASSIGNOR TO RENDROCK POWDER COMPANY, OF NEW YORK, N. Y., A CORPORATION OF NEW JERSEY.

TORPEDO.

SPECIFICATION forming part of Letters Patent No. 767,776, dated August 16, 1904.

Application filed January 6, 1904. Serial No. 187,767. (No model.)

To all whom it may concern:

Be it known that I, GEORGE G. TURNER, a citizen of the United States of America, residing at Dover, county of Kent, and State of Delaware, have invented certain new and useful Improvements in Torpedoes, of which the following is a specification, reference being had to the accompanying drawings, forming a part thereof.

10 My invention relates to torpedoes, and particularly to that class of torpedoes known as "well-torpedoes" and which are commonly employed for the purpose of "shooting" wells. My invention comprises a shell or casing 15 having a perforated conduit within same, the shell being arranged to contain the solid ingredient of an explosive comprising a solid and a liquid ingredient, the perforated conduit being provided for the purpose of admitting the liquid ingredient.

The object of my invention is to enable an explosive composed of solid and liquid ingredients arranged to be combined at the time of their use to be employed in a torpedo of 25 this character, to provide for the ready, quick, and effective saturation of the solid ingredient by the liquid ingredient when it is desired to use the device, and to render the shell impervious to moisture either before or after 30 the solid ingredient has been impregnated by the liquid ingredient.

My invention further consists in certain novel details of construction and combination of parts, as will be hereinafter more fully set forth.

I will now proceed to describe a torpedo embodying my invention and will then point out the novel features in claims.

In the drawings, Figure 1 is a view in central longitudinal section of a torpedo embodying my invention. Fig. 2 is a view in side elevation of the torpedo, partly broken away in section and showing a funnel and vent-pipe connected thereto arranged to be employed for the purpose of impregnating the solid ingredient with the liquid ingredient in preparing the torpedo for use.

The torpedo as shown comprises an outer

cylindrical shell *a*, having a pointed cap or head *b* at one end and closed at the other end 50 by means of a plug or closure *c*.

Within the casing *a* is a conduit *d*, said conduit extending through the end of the shell, and preferably through the plug *c*, to the exterior thereof. A cap *e* closes the end 55 of the tube and seals same against admittance of air, moisture, or the like.

The class of explosive which I desire to employ is that in which two ingredients are employed—one a solid ingredient, such as 60 chlorate of potash, and the other a liquid ingredient, such as nitrobenzol. These two ingredients are non-explosive in themselves, but when combined form a high explosive. It is the purpose of my present invention to 65 fill the shell with the solid ingredient, as powdered chlorate of potash, which may be readily done by inserting same through the opening closed by the plug *c* and then sealing the opening by inserting and securing the 70 plug *c* in position and then shipping the torpedo or cartridge thus formed to the location where it is intended to be used. The liquid ingredient may be shipped separately in a can or bottle and need not be applied until such 75 time as it is desired to actually use the torpedo. At such time the nitrobenzol or other liquid ingredient may be applied by removing the cap *e* and attaching a pipe *f* to the conduit *d*, as shown in Fig. 2 of the drawings. 80 A funnel *g* may be conveniently attached to this pipe and the liquid ingredient poured into the funnel. From the funnel the liquid ingredient will pass through the pipe *f* into the conduit *d* and thence through the perforations therein into the solid ingredient in the shell *a* to thoroughly and uniformly impregnate same. The correct and predetermined 85 quantity of liquid ingredient may be introduced into the funnel, and sufficient time will 90 be allowed for the liquid ingredient to pass into the shell and thoroughly impregnate the solid ingredient.

The device being hermetically sealed, I preferably provide a vent, as at *h*, which may be 95 ordinarily kept closed by means of a cap *i*.

When applying the liquid ingredient, I remove the cap *e* and may, if desired, attach a vent-pipe *j*. By this means ample provision is made for the escape of air from within the shell displaced by the incoming liquid ingredient, while the liquid will be prevented from flowing out with the air.

In order to prevent the solid ingredient, which is generally in a powdered form, from escaping through the conduit-perforations, and thus plugging up the conduit, I provide a shield of suitable form, which shield may conveniently be composed of a tubular strip of fabric, such as muslin, as shown at *k* in the drawings, such shield being arranged around the tube, of which the conduit is composed.

It will be seen that after the shell has been filled with the solid ingredient and the plug *c* hermetically sealed and the caps *e* and *i* securely fastened in position the cartridge thus formed may be kept indefinitely, as the ingredient contained therein will be entirely protected from moisture or other destructive element and may be handled freely without danger of injury to the material or explosion thereof. When it is desired to employ the cartridge as an explosive, the solid ingredient may be impregnated by the requisite quantity of liquid ingredient and the cartridge may be once more sealed up, so that it will be again impervious to action from exterior causes. Thus the torpedo so formed will be watertight and may be inserted into wet holes and employed for well-shooting and similar purposes.

While I have termed the device herein a "torpedo" both before and after the liquid ingredient has been applied, it will be understood, of course, that prior to the application of the liquid ingredient the charge is not an explosive one.

What I claim is—

1. As an article of manufacture, a device of the class described, comprising an outer shell and an inner perforated conduit arranged longitudinally thereof; and an explosive ingredient, itself inexplosive until combined with another ingredient, said ingredients combined forming an explosive mass, contained between the outer shell and the inner conduit.

2. As an article of manufacture, a device of the class described, comprising an outer shell,

an inner perforated conduit arranged longitudinally thereof, and chlorate of potash contained between the inner conduit and the outer shell, the said inner conduit adapted to receive and convey a liquid ingredient to the chlorate of potash to combine with same to form an explosive.

3. As an article of manufacture, a device of the class described, comprising an outer shell, an inner perforated conduit arranged longitudinally thereof and opening through the shell at one end, a cap or closure for the said conduit, a vent for the shell provided with means for closing same; and an explosive ingredient, itself inexplosive until combined with another ingredient, said ingredients combined forming an explosive mass, contained between the outer shell and the inner conduit.

4. As an article of manufacture, a device of the class described, comprising an outer shell, an inner perforated conduit arranged longitudinally thereof and opening through the shell at one end, a cap or closure for the said conduit, a vent for the shell provided with means for closing same; and chlorate of potash contained between the outer shell and the inner conduit, the inner perforated conduit arranged to receive and convey a liquid ingredient to the chlorate of potash to combine with same to form an explosive.

5. In a torpedo of the class described, the combination with an outer shell and a perforated conduit arranged longitudinally of the shell, of a shield or guard for the said perforated conduit.

6. In a torpedo of the class described, the combination with a closed outer shell and a perforated conduit arranged longitudinally, of a vent for said outer shell and means for closing said vent.

7. In a torpedo of the class described, the combination with an outer shell *a*, pointed at one end *b*, and closed at the other end by a plug *c*, of a perforated pipe *d* arranged longitudinally of the said shell and extending through the plug *c*, a cap *e* for the said pipe, a shield *k* therefor, a vent *h* for the shell, and a cap *i* for the said vent.

GEORGE G. TURNER.
